UNITED STATES PATENT OFFICE

STROUD JORDAN, OF BROOKLYN, NEW YORK, ASSIGNOR TO APPLIED SUGAR LABORATORIES, INCORPORATED, OF NEW YORK, N. Y., A CORPORATION OF NEW YORK

METHOD OF TREATING TOBACCO LEAVES, PROCESS OF PRODUCING A COMPOSITION FOR USE IN THE PRACTICE OF THE METHOD, AND RESULTANT COMPOSITION

No Drawing.

Application filed March 7, 1932. Serial No. 597,426.

My invention relates to a method of treating tobacco leaves, a process of producing a composition for use in the practice of the method, and the resultant composition.

5 An important object of the invention is to provide a composition which may be sprayed or otherwise applied to the tobacco leaves so that moisture will be retained therein, the pliability of the leaves increased, and the combustion of the leaves promoted.

In the manufacture of cigarettes, it is common practice to employ glycerine, in amounts sometimes exceeding three pounds for each one hundred pounds of finished and cut tobacco. This is done for the express purpose of increasing pliability and retaining moisture. There can be no objection to the use of glycerine on tobacco intended for purposes other than smoking, but when tobacco thus treated is burnt, combustion is retarded, causing the formation of objectionable volatile products. A product of such decomposition is acrolein, a volatile, colorless, liquid poison, which is intensely irritating to the eyes, nose and throat. Acrolein is not a natural constituent of tobacco smoke, but is formed when glycerine or other materials which contain notable quantities of fat, are burnt.

30 Carbon monoxide is also an objectionable constituent of tobacco smoke which may be formed when insufficient oxygen is present to promote proper combustion. Like acrolein, carbon monoxide is a poison, and should

35 be eliminated. The elimination of carbon monoxide may be effected, if oxygen is present in a sufficient quantity, and all carbohydrates and cellular fibre will be changed into carbon dioxide and water vapor, eliminating the tarry decomposition products, which discolor teeth and cling to the throat.

To overcome the objections enumerated, I provide a composition embodying the present invention. The composition embodying 45 my invention will retain moisture, produce

increased pliability and at the same time promote combustion. My composition comprises materials or elements naturally present in the tobacco leaf, and this prevents the formation of harmful products, which occur when other materials are added to the tobacco leaf, such as glycerine, upon the tobacco being smoked. My composition comprises as a suitable material, calcium nitrate, and while calcium nitrate as such may not be present in the tobacco leaf, still its constituents, calcium, and nitrates, are both present in the tobacco leaf. My composition further comprises invert sugar. Sugars may or may not be present in the tobacco leaf, according to the type examined, but dextrose and levulose are both found in the component parts of the tobacco plant, and are also found in commercial invert sugar. The proportions of the materials constituting my composition, necessary to cause the cigarette tobacco to have the proper moisture, pliability and combustibility, will, obviously, vary. As an example, in the treatment of flue-cured tobacco, whereby sugars and gums have not been entirely removed in the process of curing, different proportions of materials will be necessary, than when air-cured tobacco is treated. In air-cured tobacco, sugars have been changed into corresponding acids, during the curing process, which is a slow process of starvation, and this process of curing has entirely changed the composition of the leaf.

It is not desired to promote complete combustion of the tobacco in any type of cigarette or smoking tobacco, for taste and aroma of smoke depend to a large extent upon volatile products formed by destructive distillation. A regulation of combustion, so that carbon monoxide, acrolein, and other undesirable compounds will be eliminated from the smoke, is all that is desired. My composition is adapted to be used to replace glycerine, which is employed in the treatment of tobacco, and my composition renders it possible to promote

combustion to a suitable degree, and prevent the formation of carbon monoxide and acrolein, both of which are highly desirable features.

5 As an illustration of my composition suitable for this purpose, I combine the following ingredients in the proportions stated:

	Parts by weight
Invert sugar syrup of not less than 75	
10 Brix	260
Calcium nitrate, of crystallized form	100
Water	260

15 In combining these ingredients, the crystallized calcium nitrate is first dissolved in the water, and the invert sugar syrup is then added. The mixture is stirred until a complete saturation takes place. This composition produces a solution of approximately the 20 same specific gravity as 95% glycerine, and this solution may be used as a substitute for glycerine in the treatment of the cured tobacco leaves, whereby the advantages above enumerated will be obtained, and the disadvantages 25 encountered in connection with the use of ordinary glycerine will be eliminated. My solution may replace glycerine pound for pound in the treatment of tobacco leaves. The calcium nitrate present will attract and retain 30 large quantities of moisture, while at the same time it is an oxygen bearer, and will yield oxygen, upon the combustion of the tobacco leaf, to properly promote combustion. The invert sugar present has a beneficial effect 35 in the production of taste and aroma, and also from its nature will hold any short pieces of tobacco produced in the cutting process. Further, there is an intimate co-action between the calcium nitrate and the invert sugar in the 40 liquid mass. When the calcium nitrate is mixed with the invert sugar, or other suitable sugars in solution, the characteristic sticky feel of the sugar syrup is replaced by one which is substantially greasy, and the resulting 45 liquid mass penetrates the tobacco leaf more readily than when sugars alone are used in solution. As a result of this, breakage encountered in the cutting of tobacco, whereby dust and shorts are produced, is materially 50 lessened.

55 The liquid mass thus produced may be sprayed upon the cured tobacco leaves intended for cigarette tobacco, in suitable amounts, as is customary in the use of glycerine, while the leaves are still whole and before they are cut into the characteristic shreds. I may use 3 parts by weight or more of my composition to 100 parts by weight of tobacco. Since my composition has approximately the 60 same specific gravity as glycerine, it may be employed to replace glycerine pound for pound, and the use of my product will require no change in the well known process of spraying tobacco leaves with glycerine.

65 The invention is in no sense restricted to

the precise proportions of the ingredients stated, but these proportions are preferred, as it will produce a liquid mass having approximately the specific gravity of 95% glycerine.

70 The ingredients may be widely varied, depending upon the particular character of the tobacco leaves to be treated, and upon the results desired. Satisfactory results may be obtained, in some instances, by using a composition containing the following ingredients 75 combined in the proportions stated; invert sugar syrup of not less than 75 Brix, 1 to 260 parts by weight, crystallized calcium nitrate, 10 to 50 parts by weight, water, 100 to 260 parts by weight.

80 The proportions of the ingredients may be varied to suit each individual type of tobacco treated, whether the tobacco is for cigar, pipe or cigarette smoking. If the water is decreased, while the amounts of the other ingredients remain the same, the solution is heavier; if the calcium nitrate is decreased while the amounts of the other ingredients remain the same, combustion is retarded; if the amount of invert sugar is decreased, while the other ingredients remain the same, the binding effect of the solution will be reduced.

85 While I have described my composition as used in the treatment of tobacco leaves, and as a substitute for glycerine, in such treatment, yet the composition is not necessarily restricted to such use, as it may be used for other purposes, where it would be advantageous to use glycerine or a similar liquid mass.

90 It is to be understood that the form of my invention herewith shown and described is to be taken as a preferred example of the same and that various changes in the proportions of the several ingredients may be resorted to, and that the order of the steps of the method 95 for producing the composition, may be varied, and that known chemical equivalents may be employed, without departing from the spirit of my invention, or the scope of the subjoined claims.

100 Having thus fully described my invention, what I claim is:

1. The process of treating tobacco leaves, comprising spraying the same with a composition comprising invert sugar, calcium nitrate and water.

115 2. A liquid composition for use in spraying tobacco leaves and having approximately the specific gravity of 95% glycerine, comprising invert sugar, calcium nitrate, and water.

120 3. A liquid composition, comprising invert sugar, calcium nitrate, and water.

125 4. A liquid composition, comprising substantially 260 pounds by weight of invert sugar syrup of not less than 75 Brix, substantially 100 parts by weight of calcium nitrate, and substantially 260 parts by weight of water.

130 5. A liquid composition comprising from 1 to 260 parts by weight of invert sugar syrup

of not less than 75 Brix, substantially 10 to 50 parts by weight of calcium nitrate, and substantially 10 to 250 parts by weight of water.

5 6. A composition for spraying tobacco leaves, comprising invert sugar, calcium nitrate which will yield oxygen upon the combustion of the tobacco leaf, said calcium nitrate also acting upon the sugar to convert
10 the sticky feel to substantially a greasy feel, and water.

In testimony whereof, I affix my signature.
STROUD JORDAN.
